GASEOUS ELECTRIC DISCHARGE DEVICE

Hans Ewest, Berlin, and Georg Gaidies, Berlin-Pankow, Germany, assignors to General Electric Company, a corporation of New York

Application February 17, 1933, Serial No. 657,272
In Germany March 30, 1932

4 Claims. (Cl. 176—122)

The present invention relates to gaseous electric discharge devices generally and more particularly the invention relates to such devices in which the gaseous electric discharge is of the negative 5 glow type.

The object of the present invention is to provide an electric discharge lamp device of the negative glow type which is a line light source. Another object of the invention is to provide such 10 a device of simple structure. Still further objects and advantages attaching to the device and to its use and operation will be apparent to those skilled in the art from the following particular description.

15 In accordance with these objects the invention comprises a gaseous electric discharge lamp device of the negative glow type having two slitted, cylindrical electrodes, one of said electrodes is smaller in length and in diameter than the other 20 of said electrodes and the longitudinal axes thereof are coincident. The open slitted parts of said electrodes are in line. The cylindrical electrode of smaller length and diameter is the cathode. Substantially all the light emitted by the negative 25 glow discharge surrounding said cathode is directed through the slits in both of said electrodes. A negative glow lamp device having the above structure is a line light source useful in illuminating the dials of radio receiving sets or 30 the like.

In the drawing accompanying and forming part of this specification an embodiment of our invention is shown, in which

Fig. 1 is a front view of a negative glow discharge lamp device, and

Fig. 2 is a sectional view thereof along the line 2—2 of Fig. 1.

Like numbers denote like parts in both views of the device.

40 Referring to the drawing the new and novel lamp device comprises a container 1 having a gaseous atmosphere therein comprising a rare gas, such as neon, a metal vapor, such as mercury vapor, a mixture of rare gas and metal vapor, such as 45 a mixture of argon and mercury vapor, or a mixture of rare gases, such as a mixture of argon and neon. A base 2 is attached to said container 1 and a stem 3 is fused in said container 1. Current inleads 5 and 5' for the anode 7 and 50 current inlead 6 for the cathode 8 are sealed into the pinch part 4 of said stem 3. Said base 2 is of the well known screw base type and said anode leads 5 and 5' are connected to the button thereof while the cathode lead 8 is connected to 55 the shell part thereof. Said anode 7 and said

cathode 8 are co-axial cylindrical electrodes and the anode 7 is of greater length and diameter than said cathode 8, the ends of said anode 7 extend beyond the ends of said cathode 8 in both directions. Such cathode 8 has a longitudinal slit 11 therein and said anode 7 has a longitudinal slit 12 therein, said slits 11 and 12 are in line with each other. Said slit 11 is of the same length but is greater in width than said slit 12. Said electrodes 7 and 8 are held in a fixed position with respect to each other by wires 10 attached thereto and fused into the glass bead 9.

When the above device is put into operation the greater part of the light emitted by luminous cathode glow surrounding said cathode 8 passes 15 through the slits 11 and 12 and as slit 11 is of greater width than said slit 12 the light spreads out in a fan shaped beam from said slit 12 which is of great advantage in illuminating a comparatively large area such as the dial of a radio. 20 The lamp device is very economical to operate as its current consumption is only 2-3 watts.

While we have shown and pointed out in the annexed claims certain novel features of the invention, it will be understood that various omissions, substitutions and changes in the forms and details of the device illustrated and in its use and operation may be made by those skilled in the art without departing from the broad spirit and scope of the invention, for example, the inner wall of said anode 7 is polished to obtain a better reflection of the light emitted by the luminous negative discharge surrounding said cathode 8, said cathode 8 is of wire mesh in order that substantially all the light emitted by the negative glow discharge is available for purposes of illumination, the discharge supporting surfaces of said electrodes 7 and 8 are coated with an electron emitting material, such as activated barium oxide, to reduce the potential at 35 which the negative glow discharge starts in the device, and the slits 11 and 12 are straight or curved, as desired, and have any desired angle with respect to the longitudinal axis of said cylindrical electrodes 7 and 8.

45 What we claim as new and desire to secure by Letters Patent of the United States is:—

1. A negative glow electric discharge lamp device comprising a container, a cathode and an anode sealed therein, a gaseous atmosphere therein, said electrodes being co-axial tubes, said anode being greater in length and in diameter than said cathode and extending beyond said cathode in both directions, the side walls of said cathode and said anode being slitted, said slits 50

being in line, the slit in said cathode being greater in width than the slit in said anode.

2. An electrode structure for a negative glow electric discharge device, said electrode structure comprising a cathode and an anode, said electrodes being co-axial tubes, said anode being greater in length and in diameter than said cathode and extending beyond said cathode in both directions, the side walls of said cathode and said anode being slotted, said slits being in line, the slit in said cathode being greater in width than the slit in said anode.

3. A negative glow electric discharge lamp device comprising a container, a cathode and an anode sealed therein, a gaseous atmosphere therein, said electrodes being co-axial tubes, said anode being greater in length and in diameter than said cathode and extending beyond said cathode in both directions, the side walls of said cathode and said anode being slotted, said slits

being in line, the slit in said cathode being greater in width than the slit in said anode and spacing supports at each end of said electrodes whereby said electrodes are supported in fixed relation to each other.

4. An electrode structure for a negative glow electric discharge device, said electrode structure comprising a cathode and an anode, said electrodes being co-axial tubes, said anode being greater in length and in diameter than said cathode and extending beyond said cathode in both directions, the side walls of said cathode and said anode being slotted, said slits being in line, the slit in said cathode being greater in width than the slit in said anode and spacing supports at each end of said electrodes whereby said electrodes are supported in fixed relation to each other.

HANS EWEST.
